United States Patent Office

Des. 186,009
Patented Aug. 25, 1959

186,009

UMBRELLA

Bela Lorincz, Los Angeles, Calif.

Application August 6, 1958, Serial No. 52,074

Term of patent 3½ years

(Cl. D88—3)

Fig. 1.

Fig. 2.

Fig. 3.

Fig. 1 is a plan view of an umbrella, showing my new design in open state;

Fig. 2 is a perspective view thereof; and

Fig. 3 is a perspective view of the umbrella in closed state.

The dominant features of my design are shown in full lines. The undersurface of the umbrella is in conventional form.

I claim:

The ornamental design for an umbrella, as shown and described.
